UNITED STATES PATENT OFFICE.

JÖRGEN JÖRGENSEN, OF COPENHAGEN, DENMARK.

WATER-PURIFYING APPARATUS FOR FEED-WATER IN STEAM-BOILERS.

No. 861,989.

Specification of Letters Patent.

Patented July 30, 1907.

Application filed January 23, 1907. Serial No. 353,602.

To all whom it may concern:

Be it known that I, JÖRGEN JÖRGENSEN, a citizen of the Kingdom of Denmark, and a resident of Copenhagen, Denmark, Baldersgade 8, master blacksmith, 5 have invented new and useful Improvements in Water-Purifying Apparatus for Feed-Water in Steam-Boilers, of which the following is a specification.

My invention is an improvement in purifying apparatus for feed water, and relates especially to that class 10 of purifying apparatus wherein the feed water is mixed with lime water contained in a tank or vessel, the lime water being supplied to the feed water at definite intervals.

Referring to the drawings forming a part hereof—Figure 1 is a front view of the apparatus partly in section. 15 Fig. 2 is a plan view, and Fig. 3 is a section on the line A—A of Fig. 1.

In the embodiment shown in the drawing, 1^a is a casing in which is mounted a shaft 1, having secured 20 thereto a water wheel 1^b. The feed water passes into the casing through the pipe 1^c and is delivered therefrom through the pipe 1^d, rotating the said wheel in its passage. At 1^e, the delivery pipe is provided with a funnel-shaped opening, through which the lime water 25 is delivered into the said delivery pipe from a casing 1^g, to be presently described.

An arm 2 is fixed to the shaft 1 of the water wheel, and the free end of the arm is provided with a weight 3. An elbow lever is pivoted to the casing adjacent to the 30 shaft as at 8, and one arm 6 of the said elbow lever is adapted to be engaged by the weight, the other arm 9 of the lever being connected by a link 10 with one of the arms 11 of another elbow lever pivoted to the casing 1^g before mentioned. The other arm 12 of the said elbow 35 lever is adapted to engage a sleeve 18 slidably on a lever 19 rigidly connected with the valve stem 21, of the valve 21^a, which controls the opening in the bottom of the casing 1^g. The sleeve 18 is provided on its lower face with a cam 18^a, for engagement by the arm 12 of 40 the elbow lever, and the sleeve is normally maintained in its outermost position by a spring 20 arranged between the sleeve and a collar on the said lever. A cord 17 is connected with the sleeve 18, and is wound upon a pulley 16 secured to a shaft 16^a journaled in bearings 18^b 45 on the casing 1^g, and a second wheel 15 is secured to the shaft upon which winds a cord 14 connected with a float 13 adapted to be moved up and down in the casing by the lime water contained therein.

A disk 5 is secured to the shaft 1, and the said disk 50 is provided with a pin 4 for engaging the arm 2, whereby to turn the said arm with the shaft, and the opposite end of the shaft is provided with a disk 5^a, to which is connected a link 5^b, the said link being connected at its other end with an arm 5^c, rigid with a 55 shaft 5^e, extending across the casing 1^g, and the said

shaft has secured thereto pairs of arms 5^g, the free ends of the arms being connected by cross bars 5^h for a purpose to be hereafter described. The upper end of the arm 5^e is provided with a ring 5^k engaged by an arm 5^m secured to the upper end of the valve stem 21. 60

In operation when the feed water is introduced into the casing 1^a through the pipe 1^c, the water wheel 1^b is rotated and with it the disks 5 and 5^a. The rotation of the disk 5^a imparts an oscillating movement to the shaft 5^e through the connection of the link 5^b with the 65 arm 5^c, whereby to cause the cross bars 5^h to agitate the lime water in the casing, while through the connection of the arm 5^e with the arm 5^m, the valve stem 21 is also oscillated in order to prevent an accumulation of undissolved lime around the valve. The disk 70 5 in its rotation will carry therewith the arm 2 by means of the pin 4 engaging therewith, and once during each revolution of the arm 2 the weight 3 will engage the end 6 of the elbow lever, to move the same upon its pivot, which by means of the link 10 and the 75 elbow lever 11—12 will elevate the valve 21^a to permit a certain amount of lime water to pass into the pipe 1^d to mix with the feed water. If the casing contains a large amount of feed water, the float valve 13 will be elevated, and the spring 20 will tend to force 80 the sleeve 18 to its outermost position, so that the arm 12 of the elbow lever 11—12, will engage said sleeve at the lowest part of the cam 18, and the valve 21^a will be elevated a minimum distance. When, however, the supply of lime water is low, the descent of the 85 float valve 13 will unwind the cord on the wheel 15, thus causing the cord 17 to wind up on the wheel 16, to draw the sliding sleeve inwardly, whereby to bring the higher part of the cam in position for engagement by the arm 12. This movement of the sleeve will 90 cause a greater elevation of the valve 21^a, and as a consequence a longer opening of the said valve, so that a greater amount of lime water is admitted to the pipe 1^d.

I claim—

1. A device of the class described, comprising a casing 95 for the feed water having inlet and outlet pipes, a casing for lime water having an outlet delivering into the outlet pipe of the feed water casing, a valve normally closing said outlet, a stem connected with the valve and provided with a lateral arm, a sleeve provided with a cam slidable 100 on the arm, a spring between the sleeve and the stem, a float movable in the second casing, a shaft journaled on said casing, a wheel of relatively large diameter on the shaft, a cord connected with the float and winding on said wheel, a wheel of relatively small diameter on the shaft, a cord connected with the sleeve and winding on said small wheel, an elbow lever pivoted to the casing and having one of its arms engaging the cam, a shaft journaled in the first casing, a water wheel on the shaft within the casing, and adapted to be driven by the passage of the feed water 105 through the casing, a weighted arm journaled on the shaft outside the casing, a disk on the shaft provided with a pin for engaging the arm, an elbow lever pivoted to the said 110

- 75 casing, one of whose arms is in the path of movement of the weighted arm, and a link connecting the other arm of said lever with the other arm of the elbow lever on the lime water casing.
- 5 2. A device of the class described, comprising a casing for feed water having inlet and outlet pipes, a casing for lime water having an outlet delivering into an outlet pipe of the feed water casing, a valve normally closing said outlet, a stem connected with the valve and provided with a 10 cam slidable on the arm, a spring between the sleeve and the stem, a float movable in the second casing, a shaft journaled on the casing, a wheel of relatively large diameter on the shaft, a cord connected with the float and winding on said wheel, a wheel of relatively small diameter on the shaft, a cord connected with the sleeve and winding on said wheel, an elbow lever pivoted to the casing and having one of its arms engaging the cam, a water wheel in the feed water casing and adapted to be driven by the passage of the feed water therethrough, and a connection between 15 the wheel and the other arm of the elbow lever, whereby to operate said lever at predetermined intervals.
3. A device of the class described, comprising a casing having inlet and outlet pipes for the feed water, a casing for lime water having an outlet delivering into the outlet 20 of the feed water casing, a valve normally closing said outlet, a shaft journaled in the first-named casing, a water wheel on the shaft within the casing and adapted to be driven by the passage of the feed water through the casing, a weighted arm journaled on the shaft outside of the 25 casing, a disk on the shaft provided with a pin for engaging the arm, an elbow lever pivoted to said casing, one of whose arms is in the path of movement of the weighted arm and a connection between the other arm of the elbow lever and the valve for lifting said valve, and means for 30 varying the duration of the opening movement of said valve.
4. A device of the class described, comprising a casing having inlet and outlet pipes for the feed water, a casing for lime water having an outlet delivering into the outlet 35 of the feed water casing, a valve normally closing said outlet, a stem connected with the valve and provided with a lateral arm, a sleeve provided with a cam slidable on the arm, a float movable in said last-named casing, a connection between the float and the sleeve whereby to move said 40 sleeve on the arm, an elbow lever pivoted to the casing and having one of its arms engaging the cam, a water wheel in the first-named casing, and adapted to be driven by the passage of the feed water through the casing, and a connection between the water wheel and the other arm 45 of said elbow lever for moving said lever to open the valve.
5. A device of the class described, comprising a feed water casing having an inlet and an outlet, a casing for lime water delivering into the outlet of the first casing, a valve controlling the delivery, a water wheel in the feed 50 water casing, means controlled by the water wheel for opening the valve at predetermined intervals, and means controlled by the depth of water in the lime water casing for varying the duration of the opening movement of the valve.
- 60 6. A device of the class described, comprising a casing having an inlet and an outlet for the feed water, a casing for the lime water delivering into the outlet of the first casing, a valve controlling the delivery, means operated by the passage of the feed water through the 65 first-named casing for opening the valve at predetermined intervals, and means controlled by the depth of water in the second casing for controlling the duration of the opening movement of the valve.
7. A device of the class described, comprising a feed 70 water casing, having an inlet and an outlet, a casing for the lime water having a normally closed outlet delivering into the outlet of the feed water casing, means controlled by the passage of the feed water through the first-named casing for opening said outlet at predetermined intervals,
- 75 and means controlled by the depth of water in the second casing for varying the duration of the opening movement of the valve.
8. A device of the class described, comprising a feed water casing having an inlet and an outlet, a casing for the lime water having an outlet delivering into the outlet 80 of the first-named casing, a valve controlling the delivery, a water wheel in the feed water casing, means controlled by the water wheel for opening the valve at predetermined intervals, means controlled by the depth of water in the lime water casing for controlling the duration of the 85 opening movement of the valve, a stirrer in the lime water casing, and a connection between the water wheel and the stirrer for operating the same.
9. A device of the class described, comprising a feed water casing having an inlet and an outlet, a casing for 90 the lime water having an outlet delivering into the outlet of the first-named casing, a valve normally closing the outlet, a water wheel in the feed water casing, means controlled by the water wheel for opening the valve at predetermined intervals, means controlled by the depth of water in the lime water casing for varying the duration of the 95 opening movement of the valve, and a connection between the water wheel and the valve for rotating said valve at predetermined intervals.
10. A device of the class described, comprising a feed 100 water casing having an inlet and an outlet, a casing for lime water having an outlet delivering into the outlet of the first casing, a valve normally closing said outlet, a water wheel in the feed water casing, means controlled by the water wheel for opening the valve at predetermined intervals, 105 means controlled by the depth of water in the lime water casing for varying the duration of the opening movement of the valve, a stirrer in the lime water casing, a connection between the stirrer and the water wheel for operating the same, and a connection between the water wheel and the valve for rotating said valve at predetermined intervals.
11. A device of the class described, comprising a feed water casing having an inlet and an outlet, a casing for 115 the lime water having an outlet delivering into the outlet of the first casing, a water wheel in the feed water casing, an arm mounted for rotary movement concentric with the water wheel and having a driving connection therewith, a valve controlling the outlet of the second casing, means controlled by the rotary movement of the arm for opening 120 said valve at predetermined intervals, and means controlled by the depth of water in said second casing for varying the duration of the opening movement of the valve.
12. A device of the class described, comprising a feed 125 water casing having an inlet and an outlet, a casing for the lime water having an outlet delivering into the outlet of the first casing, a water wheel in the feed water casing, an arm mounted for rotary movement concentric with the water wheel and having a driving connection therewith, a valve controlling the outlet of the second casing, and means controlled by the rotary movement of the arm for 130 opening said valve at predetermined intervals.
13. A device of the class described, comprising a feed water casing having an inlet and an outlet, a casing for 135 the lime water having an outlet delivering into the outlet of the first casing, a water wheel in the feed water casing, a valve controlling the outlet of the lime water casing, a weighted arm journaled concentrically with the water wheel for operating said valve on the downward movement of the arm, and means in connection with the wheel for 140 lifting the arm.

Signed by me at Copenhagen, Denmark, this 5th day of January 1907.

JÖRGEN JÖRGENSEN.
